UNITED STATES PATENT OFFICE

FLOYD H. HATFIELD, OF RAWLINS, WYOMING, ASSIGNOR OF ONE-TENTH TO NATHAN R. GREENFIELD, ONE-TENTH TO THOMAS W. CRAIG, AND ONE ONE-HUNDREDTH TO GEORGE M. BERGEN, ALL OF RAWLINS, WYOMING

FOLDING TABLE

Application filed June 24, 1931. Serial No. 546,543.

This invention relates to a folding table adaptable for various purposes and which will be compact when folded to permit convenient storing in a small space and will be 5 easy to carry from one place to another and has for the primary object, the provision of a collapsible top and folding legs so arranged that the legs will automatically assume supporting position when the top is extended and will fold within the top when the latter is collapsed, thereby providing a table requiring only minimum effort on the part of a person to extend for use or to collapse for storage.

15 Another object of this invention is the provision of operating means for the legs affected by the movements of the top for folding or extending the legs in accordance with the collapsing and extending of the top and 20 which will effectively brace and hold the legs in supporting position against accidental folding when the table is in use.

A further object of this invention is the provision of a folding table of the above 25 stated character which will be simple, durable and efficient and which may be manufactured and sold at a comparatively low cost.

With these and other objects in view, this 30 invention consists in certain novel features of construction, combination and arrangement of parts to be hereinafter more fully described and claimed.

For a complete understanding of my invention, reference is to be had to the following description and accompanying drawings, in which

Figure 1 is a fragmentary side elevation illustrating a folding table constructed in 40 accordance with my invention.

Figure 2 is a similar view partly in section.

Figure 3 is a bottom plan view illustrating the operating means between the table 45 top and the legs with the latter in folded position.

Figure 4 is a similar view showing the table collapsed.

Figure 5 is a sectional view taken on the 50 line 5—5 of Figure 4.

Figure 6 is a sectional view taken on the line 6—6 of Figure 3.

Figure 7 is a view similar to Figure 6 showing the top in a collapsed position.

Figure 8 is a fragmentary sectional view 55 illustrating the means for holding the legs in a supporting position.

Figure 9 is a fragmentary sectional view taken at right angles to Figure 8.

Figure 10 is a detail sectional view taken 60 on the line 10—10 of Figure 9.

Figure 11 is a plan view illustrating one of the levers of the operating means.

Figure 12 is a detail view illustrating a universal connection between said lever and 65 one of the links of the operating means.

Referring in detail to the drawings, the numeral 1 indicates an adjustable table top including a pair of sections having telescopic relation and each section includes an 70 inner member 2 having secured thereto side and end members 3 and 4. The inner members are slidably connected by telescopic braces or members 5 whereby said members 2 may be slid toward and from each other 75 for the purpose of extending the table top. The members 2 are covered by outer plates 6 having telescopic relation and form the supporting surface for the table. The plates are bent to form marginal flanges 80 engaging the members 3 and 4 and are suitably secured thereto. Opposite sides of the outer plates 6 are formed to have telescopic relation by forming on one of said plates guides 7 slidably receiving extensions 85 8 on the other plate. This arrangement permits the top 1 to be extended or telescoped when desired and when in the latter named position, the adjacent edges of the inner members 2 have abutting engagement 90 and when in an extended position the outer plates provide a continuous supporting surface for the table.

Pairs of brackets 9 are secured to the top 1 and one pair of brackets is arranged laterally of the other pair so that the legs 10 pivoted thereto may be folded in parallelism with each other and in engagement with the inner members 2. Cushioned bumpers 11 are carried by the legs 10 at their pivoted 100

ends for engagement with the inner faces of the members 4 when said legs are in supporting position and are adapted to permit the legs to yield slightly under the influence 5 of an operating means 11. Each leg is provided with a channel shaped guide element 12 to slidably receive a brace arm 13 formed integral with the operating rod 14 journaled in brackets 15 secured to the inner 10 member 2. The brace arm extends at right-angles to the rod 14 and has a head 16 formed on its free end and slidable within the guide 12. The guide 12 adjacent one end is provided with a pin or stop 17 to be 15 engaged by the head 16 as shown in Figure 8 for the purpose of holding the leg in a supporting position as shown in Figure 8. A crank arm 18 is formed on the opposite end of the operating rod 14 from the brace 20 arm 13 and is pivotally connected to a link 18 which is in turn connected to one arm of a bell crank lever 19 by a universal connection 20. The other arm of the bell crank lever 19 is of a greater length and as 25 shown in Figures 3 and 4 the bell crank lever is pivoted to the inner member 2 as shown at 21 while the longest arm of the bell crank lever has pivoted thereto a link 22 which is in turn pivoted to the opposite inner member 2 from the inner member to which the bell crank lever is pivoted, thus 30 it will be seen that each leg is provided with an independent operating means affected by the movements of the sections of the table 35 top.

The side members 3 of the inner members are provided with suitable finger grips 23 to permit a person to obtain a firm grip upon the device when it is desired to adjust 40 the inner members 2 toward or from each other.

When it is desired to place the table in use from a position as shown in Figure 4, the operator places the fingers of the hands 45 within the finger grips and pulls the inner members 2 away from each other causing the operating means 11 to swing the legs into supporting positions and as the legs reach the last named position the heads 16 of the brace arms 13 ride over the pins or lugs 17 and engage therewith as shown in Figure 8 firmly maintaining the legs in supporting position. The cushioned bumpers 11 as shown in Figure 8 have a tendency 50 to urge the legs toward folded position maintaining the pins or lugs in engagement with the heads 16 and said bumpers will yield sufficiently to permit the legs to move for disengaging the heads 16 from the pins when 55 it is desired to fold said legs. The legs move into folding position by the sections of the table top being telescoped toward each other thereby positioning the legs within the side members 3 and 4 and against 60 65 the inner members 2 providing a compact

table which can be conveniently carried from one place to another and stored in a comparatively small space. It will therefore be seen that by adjusting the table top to its full extended position the legs will be automatically moved into supporting position and firmly held in the latter named position thereby providing a table capable of use for various purposes and which will be sturdy and substantially rigid when in use. 70 75

While I have shown and described the preferred embodiment of my invention, it will be understood that minor changes in construction, combination and arrangement of parts may be made without departing from the spirit and scope of my invention, as claimed. 80

Having thus described my invention, what I claim is:

1. A folding table comprising a telescopic sectional top, legs pivoted to the sections of said top, guides carried by said legs, stops in said guides, operating rods journaled to the sections of the top, brace arms on said rods and slidably received by the guides, heads on the brace arms to ride over and engage with the stops when said legs are in supporting position, cushioned elements carried by the legs to engage the top when the legs are in supporting position to permit said legs to yield during the movement of the heads over and into engagement with the stops, and means connected to the operating rods and to the sections of the top for causing said legs to move into folded position when the sections of the top are collapsed and to move said legs into supporting position when the sections of the top are extended. 90 95 100

2. A folding table comprising a sectional top, said sections having telescopic relation, legs pivoted to the sections, operating rods journaled to the sections, brace arms carried by said rods and slidably secured to the legs, bell crank levers pivoted to the sections and having one of their ends connected to the operating rods and their other ends pivoted to a section other than the section to which said bell crank levers are pivoted to cause the legs to move into folding position when the sections of the top are collapsed and to move the legs into supporting position when the sections of the top are extended. 110 115 120

3. A folding table comprising a sectional top, said sections having telescopic relation, legs pivoted to the sections, operating rods journaled to the sections, brace arms carried by said rods and slidably secured to the legs, bell crank levers pivoted to the sections and having one of their ends connected to the operating rods and their other ends pivoted to a section other than the section to which said bell crank levers are pivoted to cause the legs 125 130 135

to move into folding position when the sections of the top are collapsed and to move the legs into supporting position when the sections of the top are extended, lugs carried by said legs to be engaged by the brace arms for maintaining the legs in supporting position, and cushion elements carried by said legs for engagement with the top to permit the legs to have a limited movement for disengaging the brace arms from said stop.

4. A folding table comprising a top including telescopic sections, legs pivoted to the sections of the top and capable of either being folded within the top or extended relative to the top to support the latter, and an operating means connected to said legs and to the sections of the top whereby the sliding movement of the sections relative to each other to collapse the top causes said legs to fold within the top and a sliding movement of the sections in an opposite direction to extend the top causes the legs to move into supporting position.

25 5. A folding table comprising a collapsible top, folding legs for said top, operating means between the legs and top to fold the legs by the collapsing of the top and to unfold said legs into supporting position by the extending of the top and simultaneously securing said legs in the latter named position, and cushion means carried by the legs to engage the top for permitting said legs to have limited movement under the influence of the operating means for freeing said legs from the supporting position.

In testimony whereof I affix my signature.
FLOYD H. HATFIELD.
